WHEEL BALANCING WEIGHT

Bernard J. Green and Milton J. Green, Bristol, Tenn.

Application April 18, 1955, Serial No. 35,548

Term of patent 14 years

(Cl. D14—30)

FIG.1

FIG.2

FIG.4

FIG.3

Fig. 1 is a front elevational view of a wheel balancing weight, showing our new design;

Fig. 2 is a rear elevational view thereof;

Fig. 3 is a bottom elevational view thereof; and

Fig. 4 is a transverse section taken on line 4—4 of Fig. 2.

We claim:

The ornamental design for a wheel balancing weight, substantially as shown.
